This ATTORNEY

UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,192,263.

Specification of Letters Patent. Patented July 25, 1916.

Application filed September 13, 1912. Serial No. 720,151.

To all whom it may concern:

Be it known that I, GEORGE A. JOHNSON, a citizen of the United States, residing at Chicago, in the county of Cook and State of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging.

The object of my invention is to provide a draft yoke capable of being made of durable material, one from which the draw-bar is readily detachable and one of safe and cheap construction.

In the drawings forming a part of the specification, Figure 1 is a plan view of a draft yoke embodying my invention. Fig. 2 is a side elevation thereof.

Referring to the drawings, 1 represents a vertically disposed U-shaped yoke strap, 2 a transverse opening therein, 3 the upper limb and 4 the lower limb thereof, the said limbs being parallel to each other and joined at their rear ends by the preferably integral member 5. In preferable construction, the yoke is provided at its inner rear end with the filler block 6 riveted to member 5. At their forward ends, the upper and lower limbs 3 and 4 respectively are joined by a pair of V-shaped lateral loops 7—7, suitably spaced apart to receive between them the rear end 8 of the draw-bar or coupler 9. The draw-bar is provided with the transverse slot 10 to receive the preferably flat coupler key 11, which in normal position or upon forward movement of the draw-bar, engages the rear faces 12—12 of the loops 7—7. The said loops are each furnished at

their rear end with an upper and lower shoulder 13 and 14 respectively to engage the front follower and hold the followers 45 and compression-resisting members in assembled position within the yoke upon applying the same to a railway car or removing it therefrom. The loops 7—7 and the forward ends 15—15 of the yoke-strap 1 50 form the forward opening 16 within which the rear end of the coupler is received. Upon rearward movement of the draw-bar, the coupler key will not be subject to strain, as the draw-bar will directly engage the 55 front follower or parts within the yoke.

I claim:

1. A vertical draft yoke for railway draft riggings which consists of a strap of substantially U shape, the upper and lower arms of said strap being connected at their forward ends by loops, each of said loops being of substantially V shape with the apex thereof extended forwardly, the arrangement being such that where said loops connect with the arms of the strap, V shaped recesses are formed with the apices thereof extended rearwardly at the top and bottom of the yoke.

2. A metallic yoke comprising two parallel bars united at their rear ends and their opposite ends merged into arms, each arm having a web and a V-shaped flange with a bearing at the apex for a key, said arms being spaced apart to receive the end of a 75 draw bar between them, the cross sectional areas of the metal in the arms between the points (apices) and the points where the arms merge with the bars being substantially the same.

GEORGE A. JOHNSON.
